RECTIFYING HYDROCARBONS

du Bois Eastman, Port Arthur, Tex., and Loren P. Scoville, Yonkers, N. Y., assignors, by mesne assignments, to The Texas Company, New York, N. Y., a corporation of Delaware

Application January 7, 1941, Serial No. 373,396

4 Claims. (Cl. 196—11)

This invention is concerned with a fractionating or rectifying process wherein hydrocarbon liquid or reflux condensate formed or collected in the operation is subjected to reboiling or stripping and contemplates certain novel improvements in which a liquid non-miscible with hydrocarbons is introduced into the reflux condensate or unvaporized material to lower the partial pressure thereof for reboiling.

A primary object of the invention is to make possible the use of a heating or stripping medium available at lower pressure than that under which the rectifying and reboiling operation is conducted. Thus, for instance, it frequently happens that in oil refining plants steam is available only at relatively low pressures such as 100-150 lbs., while it is desired to reboil or strip distillate stocks under pressures considerably in excess of the steam pressure. Thus in rectifying or stabilizing gasoline or naphtha distillates it is desirable to conduct the operation at pressures generally in excess of 150 lbs. and ordinarily at pressures of the order of 200-400 lbs. In many plants steam is available only at pressures under 150 lbs. and cannot be obtained at higher pressures except by the installation of expensive high pressure equipment.

In accordance with our invention this low pressure steam is employed in such a way that it is made available for stripping or reboiling operations conducted at pressures considerably in excess of the existing steam pressures. In practicing the invention the relatively low pressure steam is brought into indirect heat exchange with the liquid in the reboiler and water or other suitable non-miscible liquid is introduced into such liquid to lower the partial pressure thereof so that the desired reboiling or stripping may be accomplished.

An important object of the invention is to accomplish the stabilizing or rectification of gasoline without impairing the color thereof. The practice of the invention makes possible a reduction in the maximum temperature applied in the rectifying and reboiling operation of some 50° F.—100° F. and this lowered temperature is of advantage in accomplishing the stabilization without impairment of color.

In practicing the invention the hydrocarbons to be fractionated or stabilized are introduced into a rectifying zone in which reflux condensate or residual unvaporized material is subjected to reboiling or stripping under superatmospheric pressure. Steam which may be at a pressure considerably below that obtaining in the recti-

fying and reboiling zones is brought into indirect heat exchange with the liquid or reflux condensate and as a result of the heat exchange the liquid is heated and condensation of steam occurs, the resultant condensed steam is accumulated, preferably at a temperature not materially below the boiling point under the pressure employed, and the hot condensate is introduced into the liquid in the reboiler to lower the partial pressure thereof. Thus, by the simultaneous action of the indirect heat exchange with the low pressure steam and the injection of the hot condensate from the steam into the liquid undergoing reboiling the desired stripping or reboiling of the liquid is accomplished.

In the following detailed description of the invention it will be described specifically as applied to the stabilizing of gasoline distillate.

Figure 1 is a diagrammatic elevation of an apparatus adapted for the practice of the invention.

Fig. 2 is a diagrammatic elevation of a modified form of the invention.

Referring to Figure 1 the hydrocarbon oil or distillate to be fractionated or rectified is introduced by a pump 10 to a rectifying tower 11. The tower is equipped with bubble trays or other suitable elements for promoting vapor-liquid contact. The overhead vapors or gases pass to a condenser coil 12 which discharges into a distillate receiver or gas separator 13. The tower is provided with suitable cooling or refluxing means which may include means for returning a portion of the distillate from receiver 13 to an upper section of the tower.

The heating and stripping means for the rectifying tower 11 includes a reboiler 14. A steam line 15 furnishes steam to a coil 16 disposed within the reboiler drum 14. An overflow baffle or weir 17 is provided in the reboiling drum so as to insure the maintenance of a body of hydrocarbon liquid in contact with the steam heating coil 16.

Residual unvaporized material from the bottom of tower 11 flows through a line 18 to a drip drum 19 disposed beneath the reboiler drum 14 and any water contained in the oil is separated out in the drip drum while the separated oil passes thence through a line 20 into the reboiler 14 so as to maintain a body of liquid hydrocarbon about the steam coil 16. Vapors and gases evolved in the reboiler drum 14 pass through a vapor line 21 to the tower 11. The reboiled hydrocarbon liquid flows over the weir 17 and is withdrawn through a line 22.

The heat exchange coil 16 is provided with a discharge line 23 leading to a steam trap 24 which permits the condensed water, condensed as a result of the heat exchange in the reboiler, to flow through a line 25 to a hot water accumulator or surge drum 26 wherein the water accumulates preferably at temperatures only slightly below the condensing point under the pressure employed in the operation. A line 27 may be provided communicating with the condensed steam line 25 for by-passing the accumulator 26 and a draw-off line 28 may be provided for drawing off excess water from the accumulator and returning it by way of line 27 to the steam source.

Hot water from the accumulator 26 is withdrawn through a line 29 by a pump 30 and forced through a discharge line 31 to a spray pipe 32 disposed within the reboiler 14. The pipe 32 may be formed with a plurality of perforations and it is advantageous to dispose a trough to receive the water from the pipe 32 so that the water may flow over the edges of the trough and drop down into the body of liquid being reboiled. The trough may well be provided with serrated edges so that the water will drip down in a plurality of streams. The water on coming in contact with the liquid being heated by the steam coil 16 is subjected to vaporization and serves to lower the partial pressure of the liquid. By introducing the water in a heated condition, not greatly below the condensing point of steam under the pressure employed in the operation, the lowering in the partial pressure is accomplished without any undue cooling of the liquid undergoing reboiling. The volatilized hydrocarbons and steam evolved in the reboiler drum 14 pass through the vapor line 21 to the tower 11.

The steam vapors which enter the tower 11 from the vapor line 21 are condensed in the tower, usually in the lower trays of the tower, and the condensed water is drawn off with the reflux condensate flowing through the line 18. A water separator drum 33 having a liquid level indicator 34 is disposed beneath the drip drum and receives liquid therefrom through an inclined pipe 35. The water flows through the inclined pipe 35 to the separator 33 displacing the hydrocarbon oil which is forced upwardly through the inclined pipe and the water collecting in the separator 33 is withdrawn through a line 36. If desired the water collecting in the drum 33 may be withdrawn through a line 37 communicating with the accumulating drum 26 or preferably with the pump intake line 29 so that the separated water may be pumped back to the spray line 32 in the reboiler.

It is advantageous to provide a flow controller 38 suitably connected to an orifice 39 in the discharge line 31 of the pump 30 and connected to a valve in the steam line 40 for supplying steam to the pump 30 so as to provide automatic control for the delivery of a constant amount of water to the spray pipe 32. It is also advantageous to provide a temperature controller 41 having a connection 42 to the vapor line 21 and a connection 43 to the steam line 15 so as to maintain a constant temperature in the vapor stream leaving the reboiler.

In the modification of the invention illustrated in Figure 2 the oil or distillate to be fractionated or stabilized is introduced by pump 10a to a tower 11a which is similar to the tower 11 of Figure 1. Reflux condensate and condensed steam accumulate on a trapout tray 44. The water is with-

drawn through a line 45 while the hydrocarbon distillate flows through a line 46 into which water is injected through a line 47 for passage to a reboiler. The reboiler is in the form of a shell 48 containing a plurality of tubes 49 interconnecting a bottom header 50 and a top header 51. The commingled hydrocarbon distillate and water flows through the bottom header 50 thence through the tubular elements 49 to the upper header 51. Steam is introduced into the shell 48 through a steam line 52 and is discharged through a line 53. The reboiled condensate, including volatilized water and hydrocarbons, passes through a line 54 into the lower section of the tower 11a, preferably above the liquid level therein, wherein the volatilized constituents separate from the liquid and the rectified distillate is withdrawn through a line 55. The water which is injected into the hydrocarbon distillate through the line 47 may be obtained from the condensed steam from the reboiler in a manner similar to that described in the Fig. 1 operation.

In practicing the invention with the apparatus shown in Fig. 1 gasoline distillate of, for example, about 400 F. end point which it is desired to rectify is charged to the rectifying tower 11. A cooling reflux such as a portion of the distillate from receiving drum 13 is refluxed on the tower and heat is supplied by the vapors from the reboiler to establish and maintain a temperature gradient through the tower to accomplish the desired rectification. The rectifying tower will ordinarily be under a pressure approximating 300 lbs. and the temperature in the bottom of the tower will be about 270° F. to 380° F. The overhead product from the tower which collects in the receiving drum 13 will consist essentially or entirely of normally gaseous hydrocarbons. Gasoline from the bottom of the tower together with condensed steam flows to the drip drum wherein the water is separated out while the gasoline passes to the reboiler drum 14. Steam available at 150 lbs. pressure is admitted through line 16 to the steam heating coil 15. Hot water formed from the condensed steam accumulates in the surge drum 26 at temperatures of about 340° F. to 360° F. and a constant supply of hot water is directed through the spray pipe 32 into the heated gasoline. The volatilized hydrocarbons and water vapor leave the reboiler at a temperature of about 300° F. to 450° F. When charging distillate to the rectifying tower at a rate of 200 barrels per hour the rate of water injection into the reboiler will be about 1-6 gallons per minute, the minimum amount required varying with the boiling characteristics of the distillate being rectified and with the amount of refluxing in the tower. It is convenient to provide a small opening in the weir 17 near the bottom thereof so that in case the amount of water introduced into the reboiler drum should be in excess of that which will be vaporized therein the water will flow through this opening and the accumulation of water will be prevented.

Ordinarily the steam will be condensed in the lower trays of the tower. It is advisable, however, to provide on a number of selected trays in the tower means for preventing the accumulation of water in the upper sections of the tower. An advantageous arrangement is to provide such trays with a relatively small opening in the weir or condensate overflow baffle adjacent the bottom of the tray so as to insure the draining of the water.

While we have described a particular embodiment of our invention for purposes of illustration, it should be understood that various modifications and adaptations thereof which will be obvious to one skilled in the art, may be made within the spirit of the invention as set forth in the appended claims.

We claim:

1. In the rectification of hydrocarbons, the process that comprises subjecting hydrocarbons to rectification under superatmospheric pressure in a rectifying zone to form a hydrocarbon liquid product, conducting said hydrocarbon liquid product to a reboiling zone, passing steam, under a lower pressure than that at which said hydrocarbon liquid product is maintained in the reboiling zone, in indirect heat exchange with the hydrocarbon liquid product therein to effect heating of the hydrocarbon liquid and condensation of a portion of the steam, collecting resultant water, formed in the condensation of the steam, in an accumulating zone, withdrawing water from the accumulating zone and introducing it under increased pressure into direct contact with said liquid product to lower the partial pressure thereof for reboiling, passing resultant volatilized hydrocarbons and vaporized water from the reboiling zone to the rectifying zone and subjecting said volatilized hydrocarbons and water vapors to reflux condensation therein.

2. In the rectification of hydrocarbons wherein the hydrocarbons are subjected to rectification and a liquid product thereof subjected to reboiling under superatmospheric pressure, the process that comprises passing steam in indirect heat exchange with hydrocarbon liquid in the reboiling zone, under a pressure lower than that obtaining in the reboiling zone, to effect heating of the hydrocarbon liquid and condensation of at least a portion of the steam, introducing resultant water, formed in the condensation of the steam, into direct contact with the hydrocarbon liquid to lower the partial pressure thereof for reboiling, passing resultant volatilized hydrocarbons and vaporized water from the reboiling zone to the rectifying zone, subjecting said volatilized hydrocarbons and water vapors to reflux condensation therein, collecting resultant

hydrocarbon liquid and water, separating the water from the hydrocarbon liquid, directing the separated hydrocarbon liquid to the reboiling zone and withdrawing a final hydrocarbon liquid product from the reboiling zone.

5 3. In the rectification of hydrocarbons the process that comprises subjecting hydrocarbon oil to rectification in a rectifying zone under superatmospheric pressure, passing liquid oil from the rectifying zone to a reboiling zone maintained under superatmospheric pressure, passing steam under a pressure lower than that obtaining in the reboiling zone in indirect heat exchange with hydrocarbon oil in said reboiling zone to thereby heat the hydrocarbon oil to a vaporizing temperature and condense at least a portion of the steam, separating resultant hot water from uncondensed steam, directing separated hot water into direct contact with hydrocarbon oil in the reboiling zone to lower the partial pressure thereof, passing resultant hydrocarbon vapors and steam from the reboiling zone to the rectifying zone and subjecting hydrocarbon vapors and steam therein to reflux condensation to effect condensation of vapors and steam.

10 4. The method of rectifying gasoline that comprises subjecting the gasoline to rectification in a rectifying zone under superatmospheric pressure, passing liquid gasoline from the rectifying zone to a reboiling zone maintained under superatmospheric pressure, passing steam under a pressure lower than that obtaining in the reboiling zone in indirect heat exchange with 15 liquid gasoline in said reboiling zone to thereby effect vaporization of lighter hydrocarbons contained in the gasoline and to condense a portion of the steam, separating resultant hot water from uncondensed steam, directing separated hot water into direct contact with gasoline in the reboiling zone to lower the partial pressure thereof, passing said lighter hydrocarbons and steam from the reboiling zone to the rectifying zone and subjecting hydrocarbon vapors and 20 steam therein to reflux condensation to effect condensation of vapors and steam.
